[57] CLAIM

The ornamental design for a chair, as shown and described.

DESCRIPTION

FIG. 1 is a front perspective view of a chair which illustrates the new design;

FIG. 2 is a side elevation view thereof;

FIG. 3 is a front elevation view thereof;

FIG. 4 is a rear elevation view thereof;

FIG. 5 is a top plan view thereof, with part of the seat surface broken away to better illustrate the design; and,

FIG. 6 is an enlarged fragmentary top plan view of the seat surface of the chair.

FIG. 3.FIG. 4.FIG. 5.FIG. 6.
